wise direction, as viewed in Figures 5 and 6. The gear 39 is thus rotated by the energy stored up in the spring 34, rotation of the gear 39 being regulated by the clockwise mechanism 27, so that the lever 21 returns toward its starting position at a timed rate established by the clockwork mechanism 27.

Rotatably mounted on the bearing pin 22 above the gear 39 is a sector gear 69 formed with a radially projecting arm portion 61 extending through the upper portion 62 of the slot formed in the peripheral wall of casing 14, said upper portion 62 being a part of the main slot 28. The upper portion 62 of the slot is relatively short as compared with the major portion of the main slot, whereby the rotation of the sector gear 69 is limited to a smaller angle than the maximum rotation allowed for the lever 21.

The arm 61 is provided with an upturned lug portion 63 at its outer end, whereby the arm 61 may be manually rotated to set the alarm mechanism of the timer, as will be presently described.

A leaf spring 64 is anchored at one end to the top frame plate 26, as shown at 65, and bears on the edge of the sector gear 69 at its other end, as shown in Figure 5, biasing the sector gear 69 in a clockwise direction, as viewed in Figure 5. The leaf spring 64 thus urges the sector gear 69 clockwise to a position wherein the arm 61 abuts against the zero end of the slot portion 62.

Designated at 66 is an oscillatory alarm member comprising a pivoted arm which is provided at its end with a hammer element 67 and which is positioned so that the hammer element may strike the peripheral wall of the casing 14 responsive to rotation of the arm 66. The arm 66 is provided at the end thereof opposite the hammer 67 with an escapement member 68 (Fig. 5) which is engageable by a toothed pinion wheel 69. The pinion wheel 69 is in meshing engagement with the relatively large sector gear 69, so as to be rotated thereby responsive to the clockwise rotation of the sector gear, as viewed in Figure 5. As will be readily apparent, when the sector gear 69 rotates clockwise toward the zero position, the pinion wheel 69 is rotated, causing the alarm member 66 to oscillate and causing the hammer 67 to repeatedly strike against the peripheral wall 17 of the casing, providing an audible vibratory signal.

The top frame plate 26 is formed with an arcuate slot 70 which underlies the arm 61 and which is traversed by said arm as the sector gear 69 rotates clockwise. Pivoted in the slot 70 for rotation on an axis parallel to the plane of movement of arm 61 and substantially radial to the arcuate end wall portion 14' is the arcuate detent lever 71, said detent lever being adjacent and parallel to said arcuate end wall portion 14' and being pivoted in the slot at its midportion, as shown at 72. At one end thereof the lever is provided with an upwardly extending lug element 73 and at its opposite end the lever is provided with a depending triangular lug element 74, whereby said lug elements are movable in directions substantially perpendicular to said plane of movement of arm 61 responsive to rotation of detent lever 71. A leaf spring 75, secured to the bottom surface of the top frame plate 26 bears against the detent lever 71 subjacent the triangular detent lug 73 thereof, as shown in Figure 8, biasing the lever 71 in a counterclockwise direction, as viewed in Figure 8, the lug 73 being biased upwardly toward a position wherein it obstructs the return movement of the arm 61 after the arm has been rotated to the position thereof shown in Figure 5. The triangular lug 74 extends downwardly in the path of return movement of the indicating lever 21, and is engageable by said lever 21, as shown in Figure 8, as the lever 21 returns to its zero position.

In using the device, the indicating lever 21 is rotated in a counterclockwise direction, as viewed in Figure 5, to bring the index element 33 above a designated time value on the scale 30. The arm 61 is rotated in a counter-

clockwise direction against the force of the leaf spring 64 until said arm moves past and is lockingly engaged by the upwardly extending triangular lug 73 on the detent lever 71. The coiled spring 34 then drives the indicating lever 21 in a clockwise direction, as viewed in Figures 5 and 6, urging the lever to return toward the zero position. The return movement of the lever 21 is regulated by the clockwork mechanism 27 in the manner above described, and after the designated time period, the lever 21 reaches its zero position, whereby it engages the depending lug 74, rotating detent lever 71 in a clockwise direction, as viewed in Figures 7 and 8, thus causing the lug 73 to slip below the arm 61. This releases the sector gear 69, and allows the leaf spring 64 to drive the sector gear clockwise, as viewed in Figure 5, causing the pinion wheel 69 to actuate the escapement member 68 and oscillate the arm 66, producing the vibratory audible signal caused by the periodic impact of the hammer 67 against the peripheral wall 17 of the timer casing.

20 A stop lug 80 is provided on the end of lever 71 adjacent the depending triangular lug 74, the stop lug 80 being engageable with the top frame plate 26 to limit the counterclockwise rotation of the lever 71 to the position thereof shown in Figure 7, under the biasing force of the leaf spring 75.

25 As will be readily understood, the timer may be employed to provide a signal when a designated time period has elapsed, for example, a parking time limit, or other designated time period, notifying the person concerned of the elapse of said designated time.

30 The ratchet teeth 59 may be formed on the gear 39 in any suitable manner, for example, may be die stamped on the gear wheel 39.

35 While a specific embodiment of an improved personal timer device has been disclosed in the foregoing description, it will be understood that various modifications within the spirit of the invention may occur to those skilled in the art. Therefore, it is intended that no limitations be placed on the invention except as defined by 40 the scope of the appended claim.

45 What is claimed is:

A personal timer comprising a relatively flat casing adapted to be carried by a person and having an arcuate end wall portion provided with an elongated slot, an indicating lever pivoted in the casing for movement parallel to the plane of the casing and extending through said slot, a time scale secured externally to said casing and extending along said slot adjacent the external end of said lever, spring means connected between the lever and the casing

50 biasing the lever toward a normal position adjacent one end of said slot, a clockwork mechanism in said casing, means coupling the lever to said clockwork mechanism, said mechanism being formed and arranged to regulate the return movement of said lever toward said normal position after it has been rotated to a designated position on said time scale, an oscillatory alarm member in the casing, escapement means drivingly coupled to said alarm member, a rotary drive member mounted for rotation in a plane parallel to the plane of movement of said lever

60 and drivingly coupled to said escapement means, a spring mounted in the casing and bearing on said rotary drive member, means to rotate said drive member to a position to tension said spring, an arcuate detent lever disposed adjacent to and parallel to said arcuate end wall portion and pivoted thereto on an axis parallel to the plane of movement of said indicating lever and substantially radial to said arcuate end wall portion, said arcuate detent lever being located between the planes of movement of the indicating lever and the drive member, a detent lug on one end portion of the detent lever lockingly engageable with said drive member, and a cam element on the other end portion of the detent lever cammingly engageable by the indicating lever when said indicating lever returns to said normal position, to rotate said 70 75 detent lever in a direction to disengage said detent lug

from the drive member, whereby to allow said drive member to oscillate said alarm member.
